(57) **CLAIM**

The ornamental design for a train game set, as shown and described.

DESCRIPTION

FIG. 1 is a top perspective view showing a train component of our new design for a train game set;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a top perspective view showing the train component with its parts in a separated state;
FIG. 9 is a top perspective view showing a first game piece component of the train game set;
FIG. 10 a left side elevational view thereof;
FIG. 11 a right side elevational view thereof;
FIG. 12 is a front elevational view thereof;
FIG. 13 is a rear elevational view thereof;
FIG. 14 is a bottom plan view thereof;
FIG. 15 is a top plan view thereof;
FIG. 16 a top perspective view showing a second game piece component of the train game set;
FIG. 17 a left side elevational view thereof;
FIG. 18 a right side elevational view thereof;
FIG. 19 is a front elevational view thereof;
FIG. 20 is a rear elevational view thereof;
FIG. 21 is a top plan view thereof;
FIG. 22 is a bottom plan view thereof;
FIG. 23 a top perspective view showing a third game piece component of the train game set;
FIG. 24 a left side elevational view thereof;
FIG. 25 a right side elevational view thereof;
FIG. 26 is a front elevational view thereof;
FIG. 27 is a rear elevational view thereof;
FIG. 28 is a top plan view thereof;
FIG. 29 is a bottom plan view thereof;
FIG. 30 a top perspective view showing a fourth game piece component of the train game set;
FIG. 31 a left side elevational view thereof;
FIG. 32 a right side elevational view thereof;
FIG. 33 is a front elevational view thereof;
FIG. 34 is a rear elevational view thereof;
FIG. 35 is a top plan view thereof;
FIG. 36 is a bottom plan view thereof;
(Continued)

FIG. 37 a top perspective view showing a fifth game piece component of the train game set;
 FIG. 38 a left side elevational view thereof;
 FIG. 39 a right side elevational view thereof;
 FIG. 40 is a front elevational view thereof;
 FIG. 41 is a rear elevational view thereof;
 FIG. 42 is a top plan view thereof;
 FIG. 43 is a bottom plan view thereof; and,
 FIG. 44 a top perspective view showing the train game set with its components in an assembled state.
 The evenly-dashed broken lines in the drawings illustrate the portions of the train game set that form no part of the claim.
